UNITED STATES PATENT OFFICE.

CHARLES L. SWIFT, OF PEABODY, MASSACHUSETTS.

FUSIBLE LINK FOR SPRINKLER-HEADS.

1,323,422.

Specification of Letters Patent.

Patented Dec. 2, 1919.

Application filed March 11, 1919. Serial No. 281,920.

To all whom it may concern:

Be it known that I, CHARLES L. SWIFT, a citizen of the United States, residing at Peabody, in the county of Essex and State 5 of Massachusetts, have invented certain new and useful Improvements in Fusible Links for Sprinkler-Heads, of which the following is a specification.

This invention relates to sprinkler heads 10 for stationary fire extinguishing systems of that class in which pipe lines are equipped at suitable intervals with normally closed heads designed to be automatically opened upon the fusing of an element thereon so as 15 to permit the discharge of water from the pipes through said heads and onto the objects in the vicinity of the pipes.

The invention further aims to provide a 20 sprinkler head of this type so constructed that the same will act with certainty and in a highly efficient manner in the event of fire in the vicinity of the head.

The invention further contemplates the 25 provision of a sectional fusible link adapted to be interposed between the supporting arms or struts of the head and so constructed that immediately upon fusing of the material connecting the link sections, the latter will separate and automatically open the 30 head to permit the discharge of water from the supply pipe.

A further object of the invention is to provide a fusible link for sprinkler heads including overlapping plates having offset portions or shoulders which interengage when the link is in position upon the sprinkler head and serve to prevent undue strain on the fusible material connecting said plates.

A still further object is generally to 40 improve this class of devices so as to increase their utility, durability and efficiency.

In the accompanying drawings:

Figure 1 is a perspective view of a sprinkler head provided with a fusible link embodying the present invention;

Fig. 2 is a vertical sectional view thereof;

Fig. 3 is a top plan view showing in full lines the fusible link in normal position and in dotted lines swung laterally to one side 50 of the supporting frame;

Fig. 4 is a side elevation of the fusible link detached, showing in dotted lines the manner in which the plates comprising said link are separated upon fusion of the material 55 connecting said plates;

Fig. 5 is a perspective view of the different elements comprising the head detached.

Corresponding and like parts are referred to in the following description and indicated in all the views of the drawings by the same 60 reference characters.

In the drawing, the head is illustrated as comprising a body portion or nipple 5 having its exterior walls threaded at 6 for connection with a water supply pipe indicated 65 at 7. Secured to or formed integral with the nipple 5 is an upstanding yoke or frame 8 having its upper portion provided with the threaded opening 9 for the reception of the correspondingly threaded shank 10 of 70 a deflector indicated at 11. The deflector 11 may be of any approved construction and in the present instance is shown provided with a depending scalloped flange 12 which serves to deflect or spread the water laterally over 75 the objects in the vicinity of the supply pipes. The top yoke 8 is preferably provided with a transverse aperture 13 adapted to receive a pin or other locking element, not shown, for the purpose of holding the deflector in adjusted position after it has been set.

The discharge end of the body or nipple 5 is normally closed by a valve including a 80 relatively thin metallic disk 14 and a correspondingly thick disk 15, the latter having its upper surface formed with a depression or socket 17, there being a similar socket 18 formed in the lower terminal of the shank 10 of the deflector, as shown. 90

Interposed between the valve and lower terminal of the shank 10 of the sprinkler head are readily separable supporting arms or struts 19 and 20 each provided with a conical extension 21 adapted to fit in the 85 adjacent sockets in the disk 15 and shank 10, respectively. The upper longitudinal edge of the lower arm 19 is formed with a substantially V-shaped notch 22 adapted to receive the correspondingly shaped terminal 100 of the upper arm 20, the parts being so arranged that when the arms are inserted between the deflector and valve, respectively, the notch 22 and the corresponding terminal on the arm 20 will be out of alignment with 105 the axis of the head.

Interposed between the free ends of the supporting arms 19 and 20 is a fusible link 110 preferably constructed in two sections 23 and 24, each section being preferably in the

form of a flat plate of the desired width and height to be supported between the free ends of the arms 19 and 20. The intermediate portion of the link plate or section 24 is offset laterally to provide an approximately square shoulder 25, while the terminal of the adjacent plate or section 23 is bent inwardly to form a correspondingly approximately squared portion or shoulder 26 adapted to normally bear against the shoulder 25 on the link section or plate 24. The plates or link sections 23 and 24 are normally and temporarily held in close contact with each other by the application of suitable fusible material indicated at 27. The outer ends of the link sections 23 and 24 are provided with apertures 28 adapted to receive the hooked terminals 29 of the supporting arms so as to prevent accidental displacement of the fusible link when once positioned between the arms. The link section or plate 24 preferably overlaps the mating link section 23 for the major portion of the length of the latter so as to reinforce the link and provide an extended surface for the application of the fusible material. The upper end of the link section 24 is also preferably provided with a notch 30 which registers with the adjacent aperture 28 in the link plate 23 to permit the passage of the terminal of the upper arm 20.

The end of the offset portion or shoulder 26 is also preferably curved or rounded, as indicated at 31, so as to form in effect a fulcrum when the material uniting said section is fused, as best shown by dotted lines in Fig. 4 of the drawings.

In operation the sections of the link properly fused together are interposed between the terminals of the arms 19 and 20 and the deflector 11 rotated so as to actuate the arms 19 and 20 to hold the link in position. In case of excessive heat or fire in the neighborhood of the sprinkler head the material uniting the link sections will fuse and owing to the outward rocking movement of the arms 19 and 20 the link sections will separate laterally with the parts rocking in opposite directions on the fulcrum 31 thereby releasing the valve and permitting the water from the supply pipe 5 to come in contact with the deflector and be discharged or deflected laterally over the objects to be protected.

The frame 8 and upper supporting arm 20 are provided with lugs or projections 32 which interengage when the supporting arms are swung laterally and thus prevent the fusible link from coming in contact with the supporting frame and being accidentally displaced as best shown in Fig. 3 of the drawings.

It will here be noted that by forming the sections or plates comprising the fusible link with offset portions or shoulders the latter

by engagement with each other will prevent undue strain on the fusible material and thus increase the efficiency of the device and render it absolutely safe and reliable in operation.

It will further be noted that as the material which unites the links becomes fused the stress exerted by the arms 19 and 20 will exert a pulling strain on the link in a straight line passing through the openings 75 in the link sections which receive the ends of the arms and that due to the peculiar formation of the shoulders or offset portions 25 and 26, the link 24 will first fulcrum upon the rounded edge 31 of the link 23 to approximately the extent illustrated in dotted lines in Fig. 4 of the drawings and then the said rounded edge of the said link 23 will slip from engagement with the offset portion or shoulder 25 of the link 24. This 80 tendency for the links to relatively fulcrum will result in a strain tending to separate the united faces of the links in a "tearing away" manner so that the separation is more readily effected than if the resulting 90 strain was such as to separate the links, meanwhile maintaining them in parallelism. Also inasmuch as the link 23 is provided with the rounded edge portion 31, this edge portion will readily slip from beneath the shoulder provided by the offset 95 25 without any likelihood of catching or scraping up the fusible bonding material as would likely occur if this edge were more or less sharp.

It will, of course, be understood that the fusible links may be made in different sizes and shapes and while particularly adaptable for application to sprinkler heads may be used with equally good results for any purpose for which the device is found desirable or applicable.

Having thus described the invention, what is claimed as new is:

1. A fusible link comprising sections disposed face to face, and a fusible bond between the sections uniting their faces, the sections being provided with means whereby they may be connected with stress-exerting elements, one of the sections being offset to 110 provide an approximately square shoulder, and the other section having a deflected end engaging the said shoulder and provided with a rounded terminal edge to fulcrum upon and ride over the shoulder when the 115 bond is fused and as the sections separate.

2. The combination with a sprinkler head having coacting strut arms and opposed stress-exerting elements against which the arms are fulcrumed, whereby the tendency 120 is for the outer ends of the arms to swing on arcs in opposite directions, of a fusible link comprising sections disposed face to face, and a fusible bond between the sections uniting their faces, the sections being con- 125 130

nected at their outer ends with the said arms, one of the sections being offset near one extremity to provide a shoulder and the other having a deflected end engaging
5 the said shoulder and provided with a terminal portion to fulcrum upon and ride over the shoulder when the bond is fused and as the sections separate, the opposing united faces of the sections from the point of engagement of the deflected end with said shoulder to the other extremities of the sections occupying substantially parallel planes.
10 3. A fusible link comprising sections disposed face to face, and a fusible bond between the sections uniting their faces, the sections being provided with means whereby
15

they may be connected with stress exerting elements, one of the sections being offset near one extremity to provide a shoulder and the other having a deflected end engaging
20 the said shoulder and provided with a terminal portion to fulcrum upon and ride over the shoulder when the bond is fused and as the sections separate, the opposing united faces of the sections from the point of engagement of the deflected end with said shoulder to the other extremities of the sections occupying substantially parallel planes.
25

In testimony whereof I affix my signature. 30

CHARLES L. SWIFT. [L. S.]
